UNITED STATES PATENT OFFICE.

DAVID F. VAUGHAN, OF HADDONFIELD, NEW JERSEY.

TIE-PLATE.

No. 823,827.

Specification of Letters Patent.

Patented June 19, 1906.

Application filed December 11, 1905. Serial No. 291,186.

To all whom it may concern:

Be it known that I, DAVID F. VAUGHAN, a citizen of the United States, residing at Haddonfield, Camden county, in the State of New Jersey, have invented certain new and useful Improvements in Tie-Plates, of which the following is a full, clear, and exact description, reference being had to the accompanying drawings.

10 The object of this invention is to provide a tie-plate of simple and efficient construction and adapted for use at either the meeting ends of two rail-sections or at points between the ends of a rail-section.

15 As generally stated, the invention consists in providing the tie-plate with a longitudinal rib or ribs projecting from each of its faces, arranging the rib or ribs of one face substantially at right angles to the rib or ribs of the other face and providing the tie-plate with spike-holes for the reception of spikes to secure the rail and plate to a tie or sleeper, the relative arrangement of the ribs and spike-holes being such that when one face of the 25 plate is turned up the plate may be used at the meeting ends of two rail-sections in connection with the usual splice-bar, and when the plate is given a quarter-turn horizontally and its other face turned up said plate may 30 be used at points intermediate such ends, as will be hereinafter more fully described.

In the drawings, Figure 1 is a perspective view of a tie-plate embodying my invention. Fig. 2 is a similar view as inverted. Fig. 3 35 is an elevation of the tie-plate and adjuncts as used in connection with a rail at a point away from the splice-bars uniting two rail-sections. Fig. 4 is an elevation of the tie-plate and adjuncts as used in connection with 40 a splice-bar uniting two rail-sections, the rail being shown in section. Fig. 5 is a sectional detail as on the line 5 5 of Fig. 1.

1 designates the body portion of the tie-plate, either face of which is adapted to rest 45 upon a tie or sleeper. Projecting from one face of the plate 1 away from the center thereof is a longitudinally-extending rib 2, the inner vertical wall of which is adapted to engage a splice-bar, as will be hereinafter explained. Projecting from the other face of the plate 1 at right angles to the rib 2, or substantially so, on each side of the center of 50 said plate is a pair of longitudinally-aligned ribs 3, the distance between the two pairs of ribs 3 being equal to the width of the foot-flange of a rail and the inner vertical walls of

said ribs being adapted to engage the edges of said flange, as will hereinafter appear. It may here be remarked that the tie-plate may be constructed with either one or both pairs 60 of ribs 3, or instead of employing a pair of ribs in either case one continuous rib may be used.

The plate 1 is provided with two pairs of spike-holes 4 and 6, one pair of holes 4 being adapted to receive spikes when the plate is used in connection with splice-bars and the other pair of holes 6 being adapted to receive spikes when the plate is used in connection with the rail at points away from the splice-bars. The distance between the two holes 4 70 of one pair at right angles to the rib 2 is substantially equal to the width of the foot-flange of a rail and to the distance between the two holes 6 of the other pair at right angles to the ribs 3, whereby when the plate 1 occupies one 75 position with two of its edges parallel to the rail spikes may enter one pair of holes adjacent to the edges of the foot-flange of the rail, and when the plate 1 occupies another position with its other two edges parallel to a rail 80 spikes may enter the other pair of holes adjacent to the foot-flange of a rail. The holes 6 are arranged between the pairs of ribs 3 and outwardly of the inner faces thereof, the inner edges of said holes being substantially in 85 line with the inner edges of the ribs 3, and one hole of the pair of holes 4 is arranged inwardly of the inner face of the rib 2, the distance between the inner edge of said one hole and the inner face of the rib being substantially equal to the distance between the outer edge of a splice-bar and the adjacent edge of 90 the foot-flange of a rail.

When the tie-plate is used at a joint between two rail-sections or in connection with 95 the splice-bar 7, as shown in Fig. 4, the face of the plate provided with the ribs 3 rests upon the tie 8, the ribs 3 sinking into the tie longitudinally or parallel to the grain thereof. In this position of the plate 1 the inner 100 vertical wall of the rib 2 takes against the outer edge of the splice-bar 7, and the holes 4 are in position to permit the spikes 9 to be driven into the tie 8 adjacent to the edges of the foot-flange of the rail 10.

When the tie-plate is used at a point between joints or the two ends of a rail-section, said plate is inverted and turned horizontally a quarter-turn from the position shown in Fig. 4 to bring the ribs 3 parallel 110 to the rail 10, as shown in Fig. 3. In this position of the plate 1 the rib 2 enters the tie

8 longitudinally or parallel to the grain thereof, the inner faces of the ribs 3 take against the edges of the foot-flange of the rail 10, and the holes 6 are in position to permit the 5 spikes 9 to be driven into the tie 8 adjacent to the edges of said flange.

I claim—

1. A tie-plate having a longitudinal rib projecting from one of its faces, and a longitudinal rib projecting from the other of its faces substantially at right angles to the first-named rib, said plate having a spike-hole arranged outwardly of the inner face of one of said ribs, and said plate having a spike-hole 10 arranged inwardly of the inner face of the other of said ribs, substantially as and for the purpose set forth.
2. A tie-plate having a longitudinal rib projecting from one of its faces, and a longitudinal rib projecting from the other of its faces substantially at right angles to the first-named rib, said plate having two pairs of spike-holes, the distance between the two holes of one pair at right angles to one rib 15 being substantially equal to the distance between the two holes of the other pair at right angles to the other rib, one spike-hole of one pair being arranged outwardly of the inner face of one of said ribs and one spike-hole of 20 the other pair being arranged inwardly of the inner face of the other of said ribs, substantially as and for the purpose set forth.
3. A tie-plate having two longitudinally-

aligned ribs projecting from one of its faces, and a longitudinal rib projecting from the other of its faces substantially at right angles to the first-named ribs, said plate having a spike-hole arranged between and outwardly of the inner faces of said aligned ribs, and said plate having a spike-hole arranged inwardly 40 of the inner face of said rib, substantially as and for the purpose set forth.

4. A tie-plate having two longitudinal parallel ribs projecting from one of its faces, and a longitudinal rib projecting from the other of its faces substantially at right angles to the first-named ribs, said plate having spike-holes arranged outwardly of the inner faces of said parallel ribs, and said plate having a spike-hole arranged inwardly of the inner face of said rib, substantially as and for the purpose set forth.

5. A tie-plate having a longitudinal rib projecting from one of its faces and arranged to one side of the center thereof, and having another longitudinal rib projecting from the other of its faces and arranged at right angles to the first-named rib and to one side of the center of the plate, substantially as and for the purpose set forth.

In testimony whereof I have hereunto affixed my signature.

DAVID F. VAUGHAN.
